Primary Examiner—Philip S. Hyder

[57] **CLAIM**

The ornamental design for a utility knife blade guard, as shown.

DESCRIPTION

FIG. 1 is a right side perspective view.

FIG. 2 is a right side view.

FIG. 3 is a back view.

FIG. 4 is a front view.

FIG. 5 is a top view.

FIG. 6 is a bottom view; and,

FIG. 7 is a left side view.

1 Claim, 2 Drawing Sheets*FIG. 1*

FIG. 7

FIG. 3

FIG. 5

FIG. 2

FIG. 6

FIG. 4
